UNITED STATES PATENT OFFICE.

A. W. STREETER, OF SHELBURNE FALLS, MASSACHUSETTS.

IMPROVED BRACE.

Specification forming part of Letters Patent No. 40,652, dated November 17, 1863.

To all whom it may concern:

Be it known that I, A. W. STREETER, of Shelburne Falls, in the county of Franklin and State of Massachusetts, have invented a new and useful Improvement in Carpenters' Braces or Bit-Stocks; and I do hereby declare that the following is a full, clear, and exact description of the same, reference being had to the accompanying drawing, making a part of this specification, said drawing, being a view of a brace or bit stock with my improvement applied to it and shown in section.

This invention relates to an improvement in the attaching of the knob to the end of the brace or bit-stock.

The object of the invention is to obviate the difficulty attending the wear of the working parts in the ordinary brace or bit-stock, and at the same time reduce the cost in the construction of said part of the brace or bit-stock.

To enable those skilled in the art to fully understand and construct my invention, I will proceed to describe it.

A represents the brace or bit-stock, which is constructed of metal, bent or curved in the usual form and provided at the center of its crank portion with a wooden knob, B, for the purpose of turning it. C is the knob at the end of the brace or bit-stock. This knob is of wood or any suitable material, and it is secured on a metal socket, D, which is fitted on the end of the brace or bit-stock. The end of the brace or bit-stock A which is fitted in the socket D is turned down so as to leave a stem or shank, a, and a shoulder, b, and the socket D is provided internally with

an opening of two different diameters, so as to leave a ledge or shoulder to bear or rest against the shoulder b on the brace or bit-stock. The shoulder b is near the end of the brace or bit stock, and hence a long bearing is given the socket D on the brace or bit-stock, and all lateral wear and strain are avoided. The end of the stem or shank a is riveted on the end of the socket D, and the knob C is screwed down on the socket D about one-half of its length, the screw a^x being formed on the socket about that distance.

By this invention a good bearing-surface is obtained for the socket D, and the brace or bit-stock will not be injured by wear in rotating the same, as is the case with the braces or bit-stocks of this kind as hitherto arranged, for in my improvement the greater portion of the brace or bit-stock which works in the socket D is not diminished in diameter, and the brace or bit-stock may be subjected to considerable lateral strain without injury from wear or without being liable to be bent or otherwise injured.

Having thus described my invention, what I claim as new, and desire to secure by Letters Patent, is—

The combination of the knob C and socket D with their screws a a, for the purpose of uniting said knob and socket to each other and to the bit-stock A, in the manner and for the purpose herein set forth.

A. W. STREETER.
